[57] CLAIM

The ornamental design for a cable access unit indoor outdoor housing, as shown and described.

DESCRIPTION

FIG. 1 is a front, top, and left side perspective view showing our new design for a cable access unit indoor housing in full lines, with the broken line matter being for illustrative purposes only and forming no part of the claimed design.

FIG. 2 is a right side elevational view thereof.

FIG. 3 is a bottom plan view thereof; and,

FIG. 4 is a rear elevational view thereof.
